UNITED STATES PATENT OFFICE.

CHARLES M. HILSEE, OF PHILADELPHIA, PENNSYLVANIA, ASSIGNOR TO UNDERWOOD TYPEWRITER COMPANY, OF NEW YORK, N. Y., A CORPORATION OF DELAWARE.

TYPEWRITING-MACHINE.

1,340,542.

Specification of Letters Patent. Patented May 18, 1920.

Application filed December 3, 1917. Serial No. 205,022.

To all whom it may concern:

Be it known that I, CHARLES M. HILSEE, a citizen of the United States, residing in Philadelphia, in the county of Philadelphia and State of Pennsylvania, have invented certain new and useful Improvements in Typewriting Machines, of which the following is a specification.

This invention relates to means for expeditiously locating a work-sheet in a typewriting machine.

It is customary, after writing and withdrawing a sheet, to have to release the feed rolls and introduce a new sheet around the platen and then adjust the new sheet to the platen scale, and then to restore the feed rolls before proceeding with the typing.

In a certain class of work there has to be typed only a single line upon the work-sheet, so that the time consumed in inserting and adjusting the sheet and machine is very large in proportion to the time consumed in the typing of a single line; which line, in many cases, consists of only a few figures or items. As an illustration, one class of work in which this condition arises consists of statements of a certain class, which are written day by day, only a single line appearing for each date; whereby the end of the month finds the statement completed and ready to be sent to the customer. Where the list of customers is very large, and only a single item is to be written at each insertion of the sheet, the time consumed by the common method of introduction and adjustment of the sheet, etc., is very great.

The object of my invention is to facilitate and expedite the insertion and location or registration of the sheet, so as to reduce to a minimum the time and labor required therefor.

In carrying out this invention, I arrange for the introduction and location of the sheet practically by the single motion of thrusting the sheet into the machine, so that the operator may proceed with the typing without any loss of time for the introduction and adjustment of the sheet.

Other features and advantages will hereinafter appear.

In the accompanying drawings,

Figure 1 is a perspective view of the platen and platen carriage of an Underwood front-strike typewriting machine, showing my improvements applied thereto.

Fig. 2 is a sectional view, showing the adjustment for the leading-edge gage.

Fig. 3 is a sectional side elevation of the platen, the chute and the gage, etc., showing a sheet inserted and thrust around the platen to the gage.

Fig. 4 is a perspective view of a guide-nut used in adjusting the gage.

Fig. 5 is a rear view showing a method of connecting line scales to the sides of the delivery table.

The sheet 10 is introduced around a cylindrical platen 11, the printing line or place where the types strike being upon the front of the platen, just above the scale 12. The sheet is introduced at the rear of the platen, and then dropped into a chute comprising a floor 13, which inclines downwardly and forwardly to the platen, and at 14 curves forwardly around the under side thereof, and also comprising sides 15 which constitute side gages for the sheet. In dropping the sheet into the chute, the operator thrusts it down, and its leading-edge is guided upwardly in front of the platen; the guiding means including Y-clips 16, which extend upwardly at the forward edge 17 of the chute to gently press a work-sheet against the platen. The sides of the chute extend up at 18 around the front of the platen 11. Said clips may be secured by screws 18^a to the front of the curved floor 14, Fig. 3, and may lie in recesses or notches 18^b cut in the floor 14, Fig. 1.

The feed rolls which usually run upon the bottom of the platen are omitted as being unnecessary, because the machine illustrated is to be used for a class of work in which never more than one line is written upon a sheet; so that there is no need for feed rolls; and for a similar reason the usual line-spacing handle may also be omitted from the typewriter carriage.

As the operator continues to thrust the sheet downwardly through the chute, the forward end rises along a sheet-positioning

or registry table 19 which extends upwardly and rearwardly from the delivery side of the platen, and has side gages 20 which in effect form continuations of the gages 15, 5 18 of the chute aforesaid. The table 19 may extend down close to the platen between the guides 18, Fig. 3.

The operator continues advancing the sheet until the leading-edge thereof strikes 10 a gage 21, which may be in the form of a bar extending across the registry table 19 at the delivery side of the machine, as aforesaid.

Thus, a single motion may introduce the 15 sheet and thrust it as far as it will go, thus mechanically adjusting it in position to begin typing; and no further manipulation is necessary, because the sheet will remain in its adjusted position during the typing 20 of the line, since it is held by means of clips 21^a, which are so constructed that the leading-edge of the advancing sheet will find its way thereunder and will be clipped lightly thereby. Each of these clips is in 25 the form of a light spring finger, and they are secured upon said gage 21, so as to be adjustable therewith. They rest lightly upon the floor of the table 19 at the delivery side of the machine, and curve or flare 30 upwardly and forwardly away from said table, and are constructed to yield to an advancing thrust of the sheet as it rises along said table. Therefore, a single thrust of the sheet carries it down, forwardly around the 35 platen and up in front thereof, and up in front of the registry table, and into the bite of the clips. The typing may therefore proceed without further attention to the paper, or to any devices for holding the paper in 40 the position to which it has been set.

Each statement is introduced and one line typed thereon on each business day of the month, and then withdrawn and kept with other statements, for receiving additional 45 items upon subsequent days. Each day the gage 21 is readjusted for the day's work; or, in other words, the gage is raised one step beyond the position it occupied for the previous day, so that as each sheet is inserted into the machine, and presented to 50 said gage, the space for the next line of writing thereon will register with the printing point upon the platen. Hence, the range of adjustment of the gage is equal to the 55 number of business days in a month, although, for convenience, the gage has been shown to be adjustable to thirty-one positions, by the aid of scales 22 placed upon one or more sides of the registration table. 60 These scales may be made detachable, so as to be replaceable by other gages; the gages being held on by thumb-screws 23.

These thumb-screws may pass through T-slots 24 in plates 25, 26, on which the scales

22 are formed; the vertical members of the 65 slots permitting up-and-down adjustment of the scales, and the cross-members of the slots permitting detachment of the scales. At either side of the machine the scales 22 may be formed upon a side gage 20; and, if desired, the opposite side gage may be omitted. In case it is omitted, the opposite side of the table may be provided with a scale 22, the surface of which lies even with the surface of the table 19, as at the right-hand of Fig. 75 1. For convenience in removing the sheet after typing, a finger opening 27 may be provided in the table, and a corresponding opening 28 in the gage 21, the latter being in the form of a flange formed upon a plate 80 29 extending across the table 19 and lying thereupon. Said gage may be secured by thumb-screws 30 passing through slots 31 extending from top to bottom of the table, and long enough to permit step-by-step adjustment of said scale, one adjustment for each line to be written upon the statement; or, in other words, the length of the slot may be equivalent to thirty-one line-spaces upon the statement. These thumb-screws 30 may 85 be threaded into nuts 32, Figs. 2 and 4, having bosses 33 fitting the slots 31 in the table. The clips 21^a may be in the form of light yielding spring fingers secured by screws 34 to the plate 29, to be adjusted up and down 90 together with the gage. The adjustment of the tension of each spring may be secured by a screw 35 passing through the spring and threaded into a boss 36 provided upon the plate 29.

The great range of adjustment of the gage is one of the features of the invention, since by providing for its adjustment to a fresh position for every business day of the month, it becomes practicable to typewrite statements day by day without giving any attention to the placing of the sheets beyond merely thrusting them in the machine as far as they will go. The mounting of the clips upon the gage is a further advantage, 105 because it enables them to perform their function of mechanically catching the sheet on every day of the month, regardless of the position of the gage; or, in other words, they are adjusted together with the gage from 110 day to day.

Variations may be resorted to within the scope of the invention, and portions of the improvements may be used without others.

Having thus described my invention, I 120 claim:

1. In a typewriting machine, in combination, a platen, a leading-edge gage adjustable to and from the delivery side of the platen, means to guide a work-sheet around said platen, whereby said work-sheet may be introduced into the machine and advanced into engagement with said leading-edge gage 125

- by substantially a single thrust movement, and means to grip the leading edge of a work-sheet, rendered effective by bringing said leading edge into engagement with said leading-edge gage, to assist in maintaining the work-sheet in position during the typing of a single line.
2. The combination with a platen, of a registry-table extending from the delivery portion of the platen, and of sufficient length to permit the leading edge of a work-sheet to be set to line-space typing positions, one for each day in a month, a leading-edge gage adjustable along said registry-table to any one of said line-space positions, and means to guide a work-sheet around the platen, whereby the work-sheet may be passed along a portion of said platen and brought into engagement with said leading-edge gage by substantially a single thrusting operation.
3. The combination with a platen, of a registry-table extending from the delivery portion of the platen, and of sufficient length to permit the leading edge of a work-sheet to be set to line-space typing positions, one for each day in a month, a leading-edge gage adjustable along said registry-table to any one of said line-space positions, means to guide a work-sheet around the platen, whereby the work-sheet may be passed along a portion of said platen and brought into engagement with said leading-edge gage by substantially a single thrusting operation, and means for maintaining the work-sheet in the line-space position determined by the leading-edge gage, to enable a single line to be typed on said work-sheet.
4. The combination with a platen, of a registry-table extending from the delivery portion of the platen, and of sufficient length to permit the leading edge of a work-sheet to be set to line-space typing positions, one for each day in a month, a leading-edge gage adjustable along said registry-table to any one of said line-space positions, means to guide a work-sheet around the platen, whereby the work-sheet may be passed along a portion of said platen and brought into engagement with said leading-edge gage by substantially a single thrusting operation, and a device adjustable with said leading-edge gage, rendered effective upon advance of the leading edge of the work-sheet into engagement with the leading-edge gage, to maintain the leading edge of said work-sheet in position during the typing of a single line on said work-sheet.
5. In a typewriting machine, in combination, a platen, a table at the delivery side of said platen, a leading-edge gage adjustable along said table to positions corresponding to desired line-spacing, guiding means for work-sheets, whereby introduction of a work-sheet into the machine and location of the same with respect to the leading-edge gage by a single thrusting action may be effected, and means rendered effective by such introduction and location, to hold said work-sheet in position to enable printing thereon.
6. The combination with a platen, of a chute at the introductory side of the platen and extending under the same and up in front thereof, and merging into a registry-table at the delivery side of the platen, a leading-edge gage upon said registry-table, said leading-edge gage having sufficient range of adjustment to permit its being reset step by step to successive single-line typing positions, one such position for each business day in the month, and a scale at the side of the registering-board whereby to adjust said gage, said scale mounted detachably to permit the substitution of a different scale.
7. The combination with a platen, of sheet-guiding means, a registry-table at the delivery side of the platen, comprising an opening to admit a typist's finger to remove a sheet, a leading-edge gage upon said registry-table comprising an opening register-90 ing with said first-named opening, to admit a typist's finger under the leading edge of a work-sheet, said leading-edge gage having sufficient range of adjustment to permit its being reset step by step to successive single-line 95 typing positions, one such position for each business day in the month, and a sheet-clip comprising a finger at the gage and adapted to ride lightly upon the sheet and to yield to the thrust of the sheet thereunder.
8. The combination with a platen, of sheet-guiding means including a chute at the rear of the platen having fingers below the printing point at the front of the platen to gently hold a work-sheet, a registry-table 105 at the delivery side of the platen, a leading-edge gage upon said registry-table, said leading-edge gage having sufficient range of adjustment to permit its being reset step by step to successive single-line typing positions, one such position for each business day in the month, and a device for mechanically catching the sheet against the registry-table to hold it against displacement while a line is being typed thereon.
9. The combination with a platen, of sheet-guiding means, a registry-table at the delivery side of the platen, a leading-edge gage upon said registry-table, said leading-edge gage having sufficient range of adjustment to permit its being reset step by step to successive single-line typing positions, one such position for each business day in the month, and a device for mechanically catching the sheet to hold it against displacement while a line is being typed thereon, said catching device mounted upon said gage to be adjusted therewith, and

bearing against the registry-table to hold a work-sheet thereagainst.

10. The combination of a platen, an introductory chute having means for guiding and laterally locating the work-sheet, a gage at the delivery side of the platen to which the leading end of the sheet is to be set, whereby to locate the sheet endwise with reference to the printing line, said gage having a range of adjustment to enable it to be reset step by step once for every business day in the month, for relocating the sheet so that each line written thereon will fall below the preceding line, a sheet-clip adapted to yieldingly clip a sheet to the platen adjacent the printing line, and a sheet-clip at said gage.

11. The combination of a platen, an introductory chute having means for guiding and laterally locating the work-sheet, a gage at the delivery side of the platen to which the leading end of the sheet is to be set, whereby to locate the sheet endwise with reference to the printing line, said gage having a range of adjustment to enable it to be reset step by step once for every business day in the month, for relocating the sheet so that each line written thereon will fall below the preceding line, and a sheet-clip at said gage, having a flaring portion beneath which the leading edge of the sheet is thrust, said clip constructed to yield to the thrust of the sheet.

12. The combination with a platen and sheet-guiding means, of a gage at the de-

livery end of the platen to which the leading end of the sheet may be set, for determining the position of the sheet vertically with reference to the printing line on the platen, said gage adjustable step by step to a fresh position for every business day of the month, whereby at successive insertions of the same work-sheet upon successive days of the single-line entries typed thereon will fall one below another, and means for mechanically catching the leading portion of the sheet to hold it during the typing operation.

13. The combination of a platen, an introductory chute having means for guiding and laterally locating the work-sheet, a gage at the delivery side of the platen to which the leading end of the sheet is to be set, whereby to locate the sheet endwise with reference to the printing line, said gage having a range of adjustment to enable it to be reset step by step once for every business day of the month, for relocating the sheet so that each line written thereon will fall below the preceding line, a sheet-clip at said gage, having a flaring portion beneath which the leading edge of the sheet is thrust, said clip constructed to yield to the thrust of the sheet, and a sheet-clip adapted to yieldingly clip a sheet to the platen adjacent the printing line.
